UNITED STATES PATENT OFFICE

2,504,923

DETACHABLE COVERING FOR ABRADING DRUMS

Arthur N. Emmons, Nedrow, and Gustaf N. Enlund, Syracuse, N. Y., assignors to Porter-Cable Machine Company, Syracuse, N. Y., a corporation of New York

Application August 7, 1948, Serial No. 43,143

3 Claims. (Cl. 51—194)

1

This invention relates to a detachable resilient covering for abrading drums, particularly for drums of floor sanding machines. These cylindrical drums are provided with a resilient covering of sponge rubber, or the like, to form a yielding backing for the sandpaper.

It becomes necessary to replace this yielding backing periodically. The conventional practise is to permanently cement the backing material onto the abrading drum. In order to replace the material, this requires removal of the roll from the machine, removing the material from the drum, and affixing a new covering on the drum. This procedure usually requires the drum to be returned to the manufacturer. Arrangements have been developed to demount, or detachably affix the backing material to the drum with the view of permitting the material to be removed without removing the drum from the machine. However, such arrangements now in use are of costly, complicated construction and add substantially to the weight of the drum, and do not always draw the covering smooth and evenly on the drum.

This invention has as an object a detachable abrading drum covering embodying a particularly simple and inexpensive construction which does not add any material weight to the drum, and which permits removal of the backing material with more ease and convenience than like arrangements now in use. The invention is of such structure that it can be readily used on conventional abrading drums now in use and functions in a manner to smoothly and evenly contact the covering on the entire peripheral surface of the drum.

The invention consists in the novel features and in the combinations and constructions hereinafter set forth and claimed.

In describing this invention, reference is had to the accompanying drawings in which like characters designate corresponding parts in all the views.

Figure 1 is a side elevational view of an abrading drum embodying our invention.

Figure 2 is an end elevational view of the drum.

Figure 3 is a view, similar to Figure 1, showing the opposite side of the drum.

Figure 4 is a perspective view of the detachable covering with a portion of the resilient material removed.

Figure 5 is a fragmentary sectional view of the drum taken on line 5—5, Figure 3.

These abrading drums consist of a cylindrical member 10 mounted on end plates 11 affixed to

2

a shaft 12 extending through the drum and being suitably journaled in the machine in which the drum is used.

These drums are formed on one side with a slot extending lengthwise of the drum and usually at a slight angle to the axis of the drum. This slot extends through the cylindrical member 10 and usually extends a distance into the end plates 11, see Figure 2. The purpose of this slot is to receive the ends of the sandpaper, or other sheet abrading material. A shaft is arranged at each side of the slot and is journaled at its ends in the end plates 11, one end of the shaft having an outwardly extending projection 13 for the reception of a wrench, or other tool, to effect rotation of the shafts. These shafts are formed with knurled cam surfaces which, upon rotation of the shafts, engage the ends 15 of the abrading material and draw the same into the slot, thus contracting it about the roll, the arrangement serving as a means for detachably securing the abrading sheet on the roll. A structure of this type is disclosed in Patent No. 1,836,367, issued to Arthur N. Emmons, December 15, 1931. The resilient cover herein disclosed is intended for use particularly with that type of abrading drum.

The cover consists of a pair of semi-cylindrical members 20 formed of rigid sheet material, such as sheet metal. These members are shaped and adapted to encircle the drum. Like ends of the members are formed with inwardly extending flanges 22, these flanges being positioned in the slot for receiving the ends of the abrading sheet. The opposite ends of the members 20 have secured thereto bars 23, the ends of which extend laterally beyond the sides of the members 20 and are folded back upon themselves to form projections in the form of eyes 24, see Figures 4 and 5. The bars 23 are secured to the members 20 by rivets, spot welding, or the like.

The side of the drum, opposite to the slot referred to, is formed with a second slot for the reception of the bars 23, the outer ends of this slot being recessed to receive the extra thickness indicated at 25 resulting from the eye formations 24.

A covering 26 of resilient material, such as sponge rubber, is fixedly secured to the outer surface of each of the members 20, as by being cemented thereto.

In use, the members 20 are placed upon the cylindrical portion 10 of the drum with the flanges 22 positioned in the abrading sheet receiving slot. The opposite end of the members 20 are drawn circumferentially about the surface

of the drum, as by screws 27 extending through the eye portions 24 of bars 23, and which are provided with tightening nuts 28. In this manner, the covering members are contracted tightly about the surface of the drum with the flanges 22 arranged in spaced relation to form a slot or opening 29 to receive the end portions 15 of the abrading sheet. These end portions of the members 20 may be additionally secured to the drum, as by screws 30.

It will be observed that the members 20 may be quickly and conveniently removed from the drum without removing the same from the abrading machine, and the only tool necessary to effect such removal is a common screw-driver. The covering may be likewise quickly replaced with new cover members and due to the fact that the flanges 22 and the bars 23 are positioned in slots formed in the peripheral surface of the drum, there is no possibility of the covering member sliding or creeping on the drum during the abrading operation. The members 20 are formed of relatively thin sheet steel, or the like, and these members plus the bars 23 add no appreciable weight to the abrading drum, nor do they have any appreciable effect upon the elements of the drum.

What we claim is:

1. A detachable cover for an abrading drum having a slot formed in the peripheral surface thereof and extending lengthwise of the drum, comprising a pair of semi-cylindrical members formed of rigid sheet material adapted to encircle the drum, confronting ends of said members having flanges arranged in spaced apart relation in said slot, tightening means cooperable with the opposite ends of said members to draw said members circumferentially around the drum in contracted relation thereto, and a layer of resilient sheet material fixed to the outer surface of each of said members.

2. A detachable covering for an abrading drum having a slot formed in the peripheral surface thereof and extending lengthwise of the drum, comprising a pair of semi-cylindrical members formed of rigid sheet material and adapted to encircle the drum, a resilient covering secured to the outer surface of each of said members, means cooperable to fixedly secure like ends of said members to the drum in registration with the edges of said slot, and tightening means cooperable with the opposite ends of said members to tension the members circumferentially about the drum.

3. A detachable covering for an abrading drum having slots formed in diametrically opposite sides of the peripheral surface thereof and extending lengthwise of the drum, comprising a pair of semi-cylindrical sheet metal members adapted to encircle the drum, like ends of said members having flanges arranged in one of said slots, the opposite ends of said members having bars affixed thereto and positioned in said other slot, said bars projecting beyond the sides of said members, and screw means cooperable with said projecting portions to draw said members circumferentially about the drum, and a covering of resilient material affixed to the outer surface of each of said members.
